UNITED STATES PATENT OFFICE.

LUCIAN KNIGHT, OF ROSSVILLE, ILLINOIS, ASSIGNOR TO HIMSELF AND JOHN BIVANS, OF SAME PLACE.

COMBINED HAME CLIP AND SECTION.

SPECIFICATION forming part of Letters Patent No. 510,687, dated December 12, 1893.

Application filed August 18, 1891. Serial No. 402,978. (No model.)

To all whom it may concern:

Be it known that I, LUCIAN KNIGHT, of Ross-
ville, in the county of Vermilion and State of
Illinois, have invented a new and useful Im-
5 provement in a Combined Hame Clip and
Section, of which the following is a full, clear,
and exact description.

My invention relates to an improved hame
clip and section, and has for its object to pro-
10 vide a device of simple and durable construc-
tion by means of which the trace or tug may
be secured to the hame.

A further object of the invention is to pro-
15 vide a clip which will be exceedingly durable
and strong in those parts in which ordinary
clips are weakest.

Another object of the invention is to so con-
20 struct the clip that it will hold the hame strap
out from the body of the animal in harness
and thus effectually prevent chafing, while at
the same time it will permit of the rear end of
25 the clip breaking the leverage over the wale,
thereby throwing the hame tug in a line with
the buckle, and making it easier on the horse's
shoulder.

The invention consists in the novel con-
30 struction and combination of the several parts,
as will be hereinafter fully set forth and
pointed out in the claim.

Reference is to be had to the accompanying
35 drawings forming a part of this specification,
in which similar figures of reference indicate
corresponding parts in all the views.

Figure 1 is a partial horizontal section
35 through a collar and hame, the clip being
illustrated in plan view and its yoke in sec-
tion. Fig. 2 is a side elevation of the collar
and hame, illustrating the clip also in side
40 elevation; and Fig. 3 is a detail view of the
yoke attachment to the clip.

The clip is constructed preferably of a single
piece of metal bent upon itself to form a flat
body section 10 with the eye 11 at one end and
a vertical loop 12 at the other end. The ends
45 of the metal after being manipulated to from
the eye and loop are carried one parallel with
one side of the body, and the other parallel
with the other side of said body 10 in oppo-
50 site direction and past the center of the body,
the said extremities of the metal thereby con-

stituting tangs 13. Before the clip is applied
to the hame the tangs are located some dis-
tance from the body so that a space will in-
tervene them and the body; and one tang is
passed through an eye 14 secured to the hame 55
15 until said eye is in engagement with an eye
of the clip, and a yoke 16, commonly called a
"section," is passed through the space be-
tween the opposite tang and into the loop at
the opposite end of the clip. When this is 60
accomplished the tangs are secured in close
contact with the body portion by a rivet 17,
a screw, or the equivalent thereof. By mak-
ing the clip in this manner the eye fits loosely
in the eye of the hame and permits of the nec-
65 essary freedom of movement for the hame and
the clip to adjust themselves upon the collar,
but prevents any twisting of the tug which
might cause its edge to bear against and chafe
the animal. The yoke 16 has its members 70
connected by a screw 18, as shown in Fig. 3,
capable of being readily removed; and over
the said screw and through the yoke the hame
strap is passed, as shown in Figs. 1 and 2.
When the clip is secured to the hame its cen-
75 tral portion which is flat and expanded will
bear upon the collar to such an extent as to
maintain the hame strap in a vertical or flat
position out of engagement with the animal,
thus preventing chafing. Besides keeping the 80
hame strap or tug in a vertical position when
on the collar, the central portion holds the
tangs rigidly in a line with each other without
the use of two rivets, as must be done in con-
structions where the clip is formed of two 85
pieces with their ends interlocked or over-
lapping each other. As the ends of the clip
must pass through the eye of the hame and
through the sections, respectively, they are
not wide enough to prevent the possible twist-
90 ing of the tug if the central portion were not
expanded as shown in Fig. 2. This construc-
tion also avoids any weak points as the ends
of the clip are simply doubled back upon the
central portion which permits of their being 95
thickened at the doubled portion where there
is the greatest wear, whereas, if one end of
the clip were cut away to form ears for the
reception of the bolt that holds the tug to the
clip, the clip would be weakened at the point 100

where the ears are joined to the central portion.

It will be observed that the clip is exceedingly strong as its body portion is reinforced by the tangs 13, and the said body portion is not weakened to any great extent as but a single rivet is passed through it.

It will be further observed that an eye is formed at each end of the body of the clip. Thus a pivotal connection, as it were, is effected between the hame and the hame strap. The device may be expeditiously and conveniently applied to a hame, and may be used as conveniently upon the right as upon the left-hand side. Any metal may be employed in the construction of the clip; spring metal, however, is preferred, and the yoke 16, may be and preferably is made of a cast or forged metal.

Having thus described my invention, I claim as new and desire to secure by Letters Patent—

In combination with a hame provided with an eye, of a clip, the central portion of which is broad and flat and the ends are reduced and doubled back upon the central portion and rigidly secured thereto by a single fastening, to form an eye at one end which engages with the eye of the hame, and a vertical loop at the other end, said eye and loop being thickened and a yoke or section within the loop, the ends of which are provided with a removable screw bolt, substantially as set forth.

LUCIAN KNIGHT.
